UNITED STATES PATENT OFFICE.

JOHN E. MEHAN, JR., OF VIRGINIA, MINNESOTA.

SEPARABLE INTERFITTING PINCERS.

1,281,990.

Specification of Letters Patent. Patented Oct. 15, 1918.

Application filed March 22, 1918. Serial No. 223,981.

To all whom it may concern:

Be it known that I, JOHN E. MEHAN, Jr., a citizen of the United States, residing at Virginia, in the county of St. Louis, State 5 of Minnesota, have invented certain new and useful Improvements in Separable Interfitting Pincers; and I do hereby declare the following to be a full, clear, and exact description of the invention, such as will 10 enable others skilled in the art to which it appertains to make and use the same.

The invention relates to pincers, and more particularly to the class of separable interfitting pairs of pincers.

15 The primary object of the invention is the provision of separable interfitting pairs of pincers, wherein on the interfitting thereof the same will afford multiple gripping jaws for clamping a piece of work of squared 20 formation at divers points thereof to more firmly hold the work, the pincers when separated can be used independently in the ordinary well known manner, thereby enabling the employment of the pairs of pincers together or independently of each other.

Another object of the invention is the provision of separable interfitting pairs of pincers of this character, wherein a squared 30 rod or the like piece of work can be positively and securely gripped by clamping the four sides thereof to avoid any possible slipping of the work or the pincers thereon and thus enabling the handling of the work with despatch, and also permitting the use 35 of each pair of pincers singly on the separation of the pairs should the occasion require.

A further object of the invention is the provision of a separable tool of this character, wherein the pincers can be fitted with 40 each other with despatch and also readily separated for the individual use thereof, the tool being simple in construction, thoroughly reliable and efficient in its operation, readily and quickly assembled, strong, durable and 45 inexpensive to manufacture.

With these and other objects in view, the invention consists in the features of construction, combination and arrangement of elements as will be hereinafter fully described, illustrated in the accompanying drawing and pointed out in the claims hereunto appended.

In the accompanying drawings:—

Figure 1 is a plan view of the tool showing 55 the pairs of pincers interfitted with each

other and constructed in accordance with the invention.

Fig. 2 is an end elevation.

Fig. 3 is a side elevation of one pair of pincers.

Fig. 4 is a side elevation of the other pair of pincers.

Similar reference characters indicate corresponding parts throughout the several views in the drawing.

Referring to the drawing in detail A designates generally one pair of pincers, and B another pair of pincers, the details of which will be hereinafter fully described.

The pincers A comprise the straight spaced parallel companion jaws 5 and 6 respectively formed with the reversely curved rearwardly extending handle extensions 7, which at the curvatures 8 therein adjacent to the inner ends of the jaws 5 and 6 cross each other and are pivotally connected together through the medium of a transverse pivot pin 9 which is mounted in the curvatures 8 of the handle extensions 7 at the crossing point thereof for permitting the opening 80 and closing of the jaws 5 and 6 when actuating the handle extensions in the use of the pincers.

The jaws 5 and 6 at their inner ends are formed with abutment shoulders 10 and the inner gripping faces 11 of these jaws when the latter are in parallel relation to each other are spaced apart for the interfitting of the other pair of pincers B with the pincers A in a manner presently described. 90

The pincers B comprises a pair of straight parallel jaws 12 and 13 respectively formed with reversely curved handle extensions 14, which at the curvatures 15 therein cross each other and are pivotally connected together through the medium of a transverse pivot pin 16 which is mounted in the curvatures 15 at the crossing point thereof for permitting the opening and closing of the jaws in the use of the pincers B. The handle extensions 14 at the inner edges of the curvatures 15 are cut away to form a crotch recess 17 providing an abutment shoulder 18 for the pincers A when interfitted with the pincers B. The jaws 12 and 13 of the pincers B when in parallel relation to each other contact with one another.

To interfit the pincers A and B the handle end of the latter is arranged at the jaw end of the pincers B with the handle extensions 110

2
 14 at right angles to the handle extensions 7 of the respective pincers and thereafter the crossed pivoted curvatures 15 of said handle extensions 14 are passed between the 5 jaws 5 and 6 so that the abutment shoulders 10 of the pincers A will engage with the abutment shoulders 18 of the pincers B, the curvatures 8 of the handle extensions 7 being designed to enter the recess 17 in the 10 curvatures 15 of the handle extensions 14 and in this manner the pincers A and B are separably interfitted with each other with the jaws of the respective pincers at right angles to each other so that in the use of the 15 pincers the said jaws will grip a piece of work on four sides thereof to firmly hold the same.

It is clearly obvious that the pincers A and B can be separated from each other 20 for the use thereof singly, or both of said pincers can be employed independently in the ordinary well known manner.

What is claimed is:—

1. The combination of pairs of pincers, 25 each having pivotally connected jaws, the jaws of one pair of pincers being spaced apart for removable interfitting of said pairs of pincers with the jaws of one pair at right angles to the jaws of the other pair to co- 30 operate with each other, the pairs of pincers

being formed with shoulder rests, located adjacent to the pivotal connection of the jaws thereof, whereby one pair of pincers will abut the other when interfitted therewith.

35

2. The combination of pairs of pincers, each having straight parallel jaws pivotally connected with each other and crossed reversely curved handle extensions, the jaws of one pair of pincers being spaced apart for 40 removably receiving the crossed handle extensions of the other pincers therebetween, said other pair of pincers being formed with a recess between the handle extensions for the interfitting of the other handle extensions, and shoulders formed in the recess and at the inner end of the spaced jaws for abutting engagement with each other.

45

3. A tool of the character described comprising a plurality of pairs of pincers removably interfitted with their jaws operable in intersecting planes, the jaws of each pair being at opposite sides of the plane of operation of the jaws of the other pair.

50

In testimony whereof I affix my signature 55 in the presence of two witnesses.

JOHN E. MEHAN, JR.
